ELECTRIC CONNECTOR

Archibald F. Meston, Middlesex, N. J.

Application April 24, 1936, Serial No. 76,235

3 Claims. (Cl. 173—328)

My invention has to do with the distribution of electricity and is directed to improvements in flexible and adaptable circuits, especially to connectors whereby such circuits can be readily and safely opened and closed.

It is often desirable to supply electric current to portable or alterable devices in the home and in shops and laboratories making it necessary to provide temporary or special circuits to conduct the current to the devices. Ordinarily such a circuit is made up or installed with conductors which are not connected to a current source until the circuit is ready to be used; then, by the closing of a switch or the insertion of a pronged plug, a current source is connected into the circuit. Such methods are relatively safe where the wiring is all insulated and no terminals are exposed to permit personal contact or undesirable "grounds" should the lines be inadvertently connected to a current source. But inexperienced and testing laboratories, battery charging stations, demonstration outfits, and about the home—in installing decorative lighting fixtures, for instance, it is desirable to have conductors which can be readily broken or disconnected so that one or both of the ends of the conductor thus freed can be carried through or about equipment and then again joined, or connected to selected terminals.

Wires with ordinary terminals and connectors do not permit of such manipulation with safety. If an ordinary pronged plug socket connector is pulled apart care must be taken that the exposed prongs are on the "dead" end of the line; otherwise, the prongs may come into contact with conducting substances and short the circuit or cause injury to persons who touch them. As a safety means the two conductors comprising the circuit are connected into a common pronged plug so when the plug is withdrawn from an energized socket both conductors are disconnected from the current source. This arrangement causes inconvenience where it is desirable to handle only one side of the line at a time. For instance, wiring comprising decorative lighting fixtures for Christmas trees are made at present with both ends of the lighting circuit permanently fastened into a common connector element, making it impossible to thread the wire and lights in and about the branches of the tree conveniently and in a manner that gives the most effective results.

With the present invention it is possible to open a single conductor in an energized circuit without danger to the operator or to any one

who may handle any of the parts making up the connector used to "open" or part the conductor. All conducting parts exposed by the separation of the connectors comprising the invention are disconnected from the current source by the separating action. A child or other inexperienced person can handle the detached end of the conductor even though the other end remains connected to an energized terminal.

The principal object of the invention is to provide means whereby an energized circuit can be opened and closed at one or more places in simple and safe manner.

Another object of the invention is to provide means whereby a closed and energized electrical circuit can be opened without exposing any energized conducting members.

Still another object of the invention is to include in an electrical circuit which has to be opened manually or within reach of non-technical operators a simple but safe connector all exposed parts of which are insulated from the current source when the connector is opened and no conducting parts of which are exposed when the connector is closed.

The manner in which the above and other objects are realized by the invention will now be described, reference being had to the appended drawing, in which:

Fig. 1 illustrates, in longitudinal section on line 1—1 of Fig. 2, a connector element (and a fragment of an outline of a complementary element) comprising the novel features of the invention;

Fig. 2 is an end view taken at 2—2 in Fig. 1;

Figs. 3 and 4 are cross-sections on lines 3—3 and 4—4, respectively, of Fig. 1; and

Fig. 5 is a longitudinal section on line 5—5 of Fig. 2.

Figs. 1, 2, 3, 4 and 5 illustrate the construction of a connector comprising connector element 83 and a complementary and similar element indicated by the fragmentary outline designated by numeral 82. Conductor 85, here shown as a stranded wire covered with insulation, is fastened within insulating casing 84 to switch jaw 86, by threading it through holes 96 in jaw 86 and, preferably, applying solder to the wire in the holes. Jaw 86 fits into a depression in casing 84 and is held therein by rivet 95 one end of which was anchored in casing 84 when the latter was molded.

A switch blade, or key 92 is fastened to a conducting member 88, the free end 88' of which serves as a second switch jaw, with pin 94.

91 passes through an insulating plate 89 to which member 88 is fastened with rivets 90. Switch jaws 86 and 88 are spaced apart and held in insulated relationship by an insulating plate 87 except in opening 87' in plate 87 where air insulation only separates the jaws. An opening 89' in plate 89 permits key 94 fastened to complementary connector 82 with pin 93 to enter opening 87' adjacent the ends of jaws 86 and 10 88'. After the connector elements are pressed together and key 94 has entered opening 87' (and key 92 is in a similar position in connector 82), turning the elements clockwise will cause key 94 to pass between jaws 86 and 88' short 15 circuiting them and joining electrically pins 91 and 93 to conductor 85. Simultaneously, key 92 short circuits members, similar to members 86 and 88, in element 82 and members 91 and 93 are electrically connected to the conductor, not 20 shown, that is fastened to element 82. Opening 89' is purposely cut at an angle with the plane passing longitudinally through key 92, as shown in Fig. 2, in order that key 94 will be in the same plane with key 92 after it has been turned subsequent 25 to its introduction through opening 89'. This makes for a properly aligned and securely fastened connection after the elements are turned relative to each other. Member 87 and the assembly comprising plate 89 and member 88 30 are fastened in place in casing 84 by applying thermo-plastic material, such as a vinyl resin, while hot, to the outer edge 97 of casing 84 where it contacts the periphery of plate 89.

It will be noted that when connector element 35 83 is detached from connecting element 82 causing the withdrawal of switch blade 94, connecting member 91 and member 88 to which it is attached are left insulated from member 86 and conductor 85 by insulating plate 87. Simultaneously, switch blade 92 on pin 91 is withdrawn from the switch members in element 82 and member 93 and connected parts are left insulated from any source of current connected to element 40 82. In this type of connector the parts to be exposed are left insulated from sources of current 45 immediately after separation of the elements is begun.

The pins and connecting members which 50 project from the connector elements to bring about connecting operations in opposing or complementary elements have been illustrated as preferably of bare metal such as brass strips or rods. Such pins are relatively cheap, are strong, make good electrical contacts, furnish 55 ample current carrying capacity, and require but small openings for entrance into complementary elements. It is to be understood, however, that these connecting members are not limited in shape or material to the disclosures utilized 60 herein to illustrate the invention. For instance, the connecting members may be metal coated in part by insulation.

I claim:

1. A connector for electrically joining conductors comprising complementary connector elements each of which comprises a protective enclosure, jaws of a switch supported within the 5 enclosure and insulated from each other, a conductor joined to one of said switch jaws, a switch blade connected to another switch jaw but held external of the protective enclosure, and an opening into the enclosure for the entrance of a switch blade attached to a complementary element, said connector being further characterized in that the switch blades are fastened to the respective elements in such manner that, upon bringing the elements together, the blades 10 are positioned at the entrance of the switch jaws and, upon turning the elements with respect to each other, the blades enter the jaws and short circuit them.

2. A connector for electrically joining conductors comprising complementary connector elements each of which comprises a protective enclosure, jaws of a switch supported within the 20 enclosure and insulated from each other, a conductor joined to one of said switch jaws, a switch blade connected to another switch jaw but held external of the protective enclosure, and an opening into the enclosure for the entrance of a switch blade attached to a complementary element, said connector being further characterized in that the switch blades are fastened to the respective elements in such manner that, upon bringing the elements together, the blades 25 are positioned at the entrance of the switch jaws and, upon turning the elements with respect to each other, the blades enter the jaws and short circuit them.

3. A connector for electrically joining conductors comprising a plurality of complementary elements each of which elements comprises a terminal connected to one end of a conductor, 30 means insulating and shielding the exposed portion of the conductor and the terminal, a conductive member one portion of which is supported within the insulating means in spaced relation to said terminal and is adapted to be connected 35 electrically with said terminal by inserting into the space between said conductive member and said terminal the exposed portion of a similar conductive member supported in like relation to a further terminal and the other portion of 40 which is exposed and is adapted to connect electrically said similar conductive member and its terminal, the exposed portion of said conductive member being so shaped that motion 45 in at least two directions is required to bring it into position to make electrical contact between a complementary conductive member and its terminal.
